UNITED STATES PATENT OFFICE.

WILLIAM S. MORRIS, OF ST. LOUIS, MISSOURI, ASSIGNOR OF FORTY ONE-HUNDREDTHS
TO JOHN CAESAR, OF ST. LOUIS, MISSOURI.

MOLD FOR CONCRETE POLES.

1,124,164.

Specification of Letters Patent.

Patented Jan. 5, 1915.

Application filed September 30, 1912. Serial No. 723,235.

To all whom it may concern:

Be it known that I, WILLIAM S. MORRIS, a citizen of the United States, and resident of St. Louis, Missouri, have invented certain new and useful Improvements in Molds for Concrete Poles, of which the following is a specification containing a full, clear, and exact description, reference being had to the accompanying drawings, forming a part hereof.

My invention relates to improvements in molds for concrete poles.

The object of my invention is to construct a mold especially designed for forming poles which taper longitudinally and which are cruciform in cross section in which provision is made for dismantling the entire mold in sections, in order to facilitate its handling and in order that the formed pole may be readily removed and also to provide for applying pressure to the mold, whereby the concrete will be forced into all of the parts of the mold.

With the above purposes in view my invention consists in certain novel features of construction and arrangement of parts as will be hereinafter more fully described, pointed out in the claims and illustrated by the accompanying drawings, in which—

Figure 1 shows in elevation a mold constructed according to my invention, having at intervals parts broken away; Fig. 2 is an enlarged, transverse sectional elevation showing the mold in assembled form; Fig. 3 is an enlarged detail elevation showing the arrangement of one of the levers for applying pressure to the mold; Fig. 4 is a detail perspective of one of the end blocks employed in the mold; Fig. 5 is a detail sectional elevation taken on the line 5—5 of Fig. 3; Fig. 6 is an enlarged detail sectional elevation taken on the line 6—6 of Fig. 2; Fig. 7 is a longitudinal sectional elevation of a portion of the mold taken on the line 7—7 of Fig. 2 and on a reduced scale from Fig. 2; and Fig. 8 is a transverse sectional elevation of the mold in a dismantled condition showing in section a concrete pole.

Referring by numerals to the accompanying drawings: 10 designates the base section, the body portions of which are substantially inverted V-shape in cross section, and at their lowermost margins carry integral flanges 11 which stand at an angle

of approximately forty-five degrees, or at right angles to the legs of the V. Each of the body portions of the base section 10 has at intervals between the legs of the V the webs 12, and formed integral with the flanges 11 are the feet 13 to provide means for securing the body portions of the section 10 against movements relative to their supporting base and movements relative to each other.

14 designates the sides of the mold each of which comprises a number of body portions which are V-shape in cross section and when in place have their apexes extended toward each other. The body portions of the sections 14 are each supported by a pair of webs 15 which are secured to said body portions by the flanges 16.

Formed integral with the webs 15 are the feet 17 which are secured to a base by means of the hinged-bolts 18 and the winged-nuts 19, there being slots 20 in the sides of the feet 17 for the insertion of said hinged-bolts. At the upper end of each of the webs 15 there is a pair of perforated ears 21 arranged to receive the pivoted bolts 22 for the support of a substantially rectangular frame 23. Pivotally supported in each of the frames 23 is a lever 24 carrying a cam 25.

26 designates the top sections of the mold each of which sections is V-shape in cross section, and carried by each of the sections is a pair of bridge-plates 27. At each end of each of the bridge-plates there is a guide 28 which engages with the vertical members 29 of the frame 23, and guides 29 which straddle the said side members of the frame 23. When the base, side and top body portions are assembled, as shown in Fig. 2, they form a hollow mold cruciform in cross section and tapering from end to end. Secured to each of the body portions of the sides 14 there is a plate 30, each of these plates being of a width slightly greater than the space within the mold which is to be filled with concrete. At intervals throughout the length of each of the body portions of the base section there is a socket 31, and at like intervals in the plates 30 there are openings 32 which are arranged to receive sockets 33, the sockets 33 being carried by leaf-springs 34 which are retained in place by a clip 35. The sockets 31 and 33 are arranged solely for the support of reinforcing rods, such as are shown by dotted lines in Fig. 2.

- 36 designates openings which are extended through the apexes of the side sections 14 and are arranged to receive core-pins (not shown), which form openings through the 5 body of the pole in order to receive metallic cross-arms or pole climbing devices and the like. These openings 36 are also arranged to receive pins 37 which serve as stops for the end blocks 38, such as are shown in de-
10 tail in Fig. 4. Carried by each of the top sections 26 are the stops 39 which are arranged to engage with the plates 30 in order to limit the downward movements of the sections 26 when pressure is exerted there-
15 upon by means of the levers 24.

In the practical operation, the body portions of the base section 10 are secured in alignment, as shown in Fig. 1, and the body portions of the side sections 14 are then 20 placed in position. The reinforcing, including the cross rods referred to, as placed in position in the mold and held by the sockets 31 and 33 engaging the ends of the cross rods. The mold is then filled with concrete.
25 The body portions of the top section 26 are then placed, one at a time, and by means of the levers 24 forced in the position, as shown in Fig. 2, thus compressing the concrete in the mold and causing it to be forced 30 into all of the parts of the mold and through the reinforcing. By reason of the removable blocks 38 and pins 37 poles of different lengths and weights may be made in the same mold.

35 I claim:

1. A mold, comprising a base, a pair of sides and a top, each of which is composed of several sections extending longitudinally of

the mold, means for securing the sections of the base and sides together, means carried by 40 the sections of the top for moving them relative to the sides and base to compress concrete within the mold, and devices arranged in pairs throughout the mold for holding a reinforce, one of each pair of said 45 devices being movable relative to its companion device.

2. A mold, comprising a base, a pair of sides and a top, all of which are constructed of a number of sections extending longitudinally of the mold and which sections are substantially V-shaped in cross section and combine to form a cruciform, means for detachably securing the sides to the base, means for moving the top relative to the sides to 50 compress the concrete within the mold, a plurality of sockets fixedly secured to said bottom, a plurality of sockets carried by the sides, and means for movably mounting said last mentioned sockets for the purposes 55 stated.

3. A mold, comprising a base unit, a pair of side units and a top unit, each of which comprises a number of parts, means carried by each of the parts for detachably 60 holding them in registration with the other parts, and means carried by each part of the top unit for moving them to compress concrete within the mold.

In testimony whereof, I have signed my 70 name to this specification, in presence of two subscribing witnesses.

WILLIAM S. MORRIS.
